RESILIENT MOUNTING MEANS FOR A RE-
SILENTLY SUPPORTED FEEDING MECH-
ANISM

Frederick A. Nicholson and Wilmot T. Pritchard,
Seattle, Wash., assignors to Stetson-Ross Ma-
chine Company, Seattle, Wash., a corporation
of Washington

Application December 21, 1936, Serial No. 116,963

5 Claims. (Cl. 144—242)

Our invention relates to a resilient mounting means for a resiliently supported feeding mechanism.

It is an object of this invention to provide a 5 resilient mounting means which is adapted to resiliently support a feeding mechanism, such as a feed bed or feed rolls, which feeding mechanism is adapted to feed a material, such as lumber, past an operating tool, such as a rotating cutter head.

10 This application is related to our co-pending applications, Serial Nos. 116,960, 116,961, 116,962, 116,964 and 116,965, which are being simultaneously filed herewith, and which co-pending applications claim some of the inventions herein 15 disclosed.

It is more particularly an object of the invention to provide a supporting frame, for mounting thereon a feeding mechanism, which supporting frame is mounted for movement with a pivotally 20 mounted arm and is also pivotally mounted on said arm.

It is more particularly an object of this invention to provide a resiliently supported means which will yieldingly resist movement from a pre- 25 determined position of such a mounted supporting frame.

It is also an object of this invention to provide a supporting frame for feeding means so that opposed feeding means may feed successive pieces 30 of material of varying thickness past an operating tool.

In the prior art, where a plurality of opposed feeding rolls were employed, such rolls were independently mounted so that the difference be- 35 tween two opposed rolls would conform to the varying thicknesses of pieces of material passing therebetween. Such practice, of independently mounting the feed rolls, brings about serious limitations to the feeding of a plurality of rolls and 40 is not practically applicable for use in connection with endless feed beds. When opposed endless feed beds were used in the prior art, a plurality of resilient means throughout the length of the feed bed were used each to depress a par- 45 ticular portion of the feed bed to permit the feed bed at that portion to conform independently of other portions of the feed bed to the varying sizes of material passing between feed beds. How- 50 ever, in all such prior art devices, the feed rolls or feed beds were not supported by a single support- 55 ing means and considerable troubles were en- countered when it was attempted to reverse the direction of feed of the driven feed rolls or driven feed beds.

It is an object of this invention to overcome the

difficulties of the prior art and provide an ad- justably mounted frame on which may be mounted feed rolls or a feed bed and to mount such ad- justable frame so that the feeding means thereon will conform to successive pieces of material, 5 even though such pieces of material are of vary- ing thickness. It is also an object of the inven- tion to provide a feeding mechanism which may be reversed in the direction of feed without diffi- culties obtaining thereby. 10

It is an object of this invention to provide a simple, efficient and practical mechanism for re- siliently mounting a feeding mechanism which will be practical and prevent costly shut-downs and continual repair of the mechanism. 15

It is more particularly an object of the inven- tion to provide a feeding member supporting frame, which is pivotally mounted on a pivotally mounted arm, together with resiliently mounted supporting means connected with said supporting 20 frame means and resisting pivotal movement of said frame means on or with said pivotal sup- porting means.

The above mentioned general objects of our invention, together with others inherent in the 25 same, are attained by the mechanism, illustrated in the following drawings, the same being pre-ferred exemplary forms of embodiment of our in- vention, throughout which drawings like refer- ence numerals indicate like parts: 30

Figure 1 is a view in elevation, with the feed beds shown by dot and dash lines, of a planer mechanism embodied in this invention;

Fig. 2 is a detached fragmentary view on a larger scale, partly in elevation and partly in 35 section, of the feeding means embodied in this invention;

Fig. 3 is a sectional view taken substantially on line 3—3 of Fig. 2;

Fig. 4 is a schematic view on a somewhat re- 40 duced scale, as respects Figs. 2 and 3, illustrating one position by dot and dash lines and another position by dotted lines which the feeding mecha- nism may assume as it pivots about the support- ing arm therefor; 45

Fig. 5 is a view similar to Fig. 4, showing one position by dot and dash lines and another posi- 50 tion by dotted lines which the feeding mechanism may assume upon pivotal movement of the sup- porting arm therefor; and

Fig. 6 is a view similar to Fig. 2, and on a small- 55 er scale than Fig. 2, of a modified form of the invention showing feed rolls instead of feed beds.

In describing and illustrating this invention we have shown the same as applicable in connec- 55

tion with the driving of endless feed beds and feed rolls of a planing device. It is to be expressly understood that this invention is not limited to any such specific application and the same is set forth only as illustrative of one environment in which this invention may be utilized.

In Figure 1 all of the details of the planer mechanism are not shown and such mechanism will be only generally described, as such details are not considered essential to this invention. A frame 10 supports the planer mechanism. The "infeeding" mechanism, generally indicated by 11 in Figure 1, includes an upper feed bed 18 and a lower feed bed 19, and it is the resilient mounting 5 means for a feed bed or feed rolls, such as the lower feed bed 19, which constitutes the invention of this application and the same will be particularly discussed after a general reference to the other portions of Figure 1. This "infeeding" mechanism 11 urges lumber stock past a lower cutter head mechanism 12 and an upper cutter head mechanism 13. The lumber is then urged past edge matcher mechanism indicated generally by 14. Lower and upper face pattern forming cutter head mechanisms 15 and 16 may be provided in connection with the planer mechanism. The "outfeeding" mechanism, details of which are not shown, is generally indicated by 17, and may be employed in connection with the planer mechanism. This outfeeding mechanism is the subject of our co-pending application Serial No. 113,960. This "outfeeding" mechanism serves to drive feed rolls to remove the finished lumber from the machine.

Referring to Fig. 2: Two opposed feed beds, as upper feed bed 18 and lower feed bed 19, are illustrated. One of these feed beds, such as upper feed bed 18, may have the endless feeding chain 20 supported to travel in a predetermined plane. The other feed bed, such as lower feed bed 19, is supported so that the endless feeding chain thereof may operate in a plurality of planes, see particularly Figs. 4 and 5.

The upper feed bed 18 comprises a plurality of driven sprockets 22 and 23 mounted on shafts 24 and 25, which shafts are journaled in frame 26 of the upper feed bed. This frame 26 is connected with the main frame 10 of the machine and the shafts 24 and 25 are connected with a source of power, not shown. The mounting of the frame 26 and the driving connection of shafts 24 and 25, is disclosed and described in our said related application. In view of the fact that the same constitutes no part of this invention, and in the interest of brevity, they are not here particularly disclosed or described. A plurality of rollers 27 serve to support the lower lap of the endless feeding chain 20. The rollers 27 and the type of endless feeding chain 20 to feed thereover are well known on the market and comprise one type of endless conveyor feed bed with which this invention may be utilized. Such rollers 27 and the type of chain 20 which is fed thereover, constitute no part of this invention and merely illustrate operative parts of one type of an endless feed bed. A shoe 28 is pivotally connected by pivot means 29 to arms of the bell crank levers 30. The bell crank levers 30 are pivotally supported by frame 26. The other arms of the bell crank levers 30 are pivotally connected with links 31. Links 31 slidably pass through projections 32 supported by the frame 26. Springs 33 are positioned on links 31 between the projections 32 and the nut means 34. Thus the springs 33, through the links and bell cranks illustrated, tend to urge the

shoe 28 upwardly and tend to keep the slack out of the endless feeding chain 20.

The lower feed bed 19 comprises a plurality of sprockets 35 and 36 similar to sprockets 22 and 23 of the upper feed bed 18. These sprockets are supported on shafts 37 and 38, which shafts are journaled in frame 39. Rollers, similar to rollers 27 of the upper feed bed 18, and tightener means (not shown) may be employed in connection with the lower feed bed.

An arm 41 is pivotally supported by pivot means 42 from the main frame 10 of the machine. The swinging end of the arm 41 is pivotally secured by pivot means 40 with the frame 39 of the lower feed bed 19. Thus the feed bed 19 and the endless feeding chain 21 thereover may pivot on the pivot means 40 and may assume positions, such as shown by dotted lines and dot and dash lines in Fig. 4 of the drawings. Also the arm 41 may pivot on the pivot means 42 and the lower feed bed 19 and the endless feeding chain 21 thereon may assume positions, such as shown by dotted lines or by dot and dash lines in Fig. 5 of the drawings. Thus the arm 41 serves as an upper pivotally mounted supporting means pivotally connected with the frame 39 of the lower feed bed.

Movement of the lower feed bed 19 about the pivots 40 or 42 is resisted by spring means 43, 44 and 45. A substantially horizontal link 46 is pivotally connected by pivot means 47 with the frame 39 of the lower feed bed 19, and nut means 48 is threadedly connected with the link 46. The spring 44 is slidably positioned on the link 46 and positioned between the nut means 48 and a collar 49, which collar is slidably positioned on link means 46. The spring means 45 is slidably positioned on link 46 and positioned between the collar 49 and other nut means 50. By adjusting nut means 48 and 50 the spring means 44 and 45 may be properly tensioned. The collar 49 is pivotally secured by pivot means 51 with the main frame 10 of the machine. Thus, the spring means 44 and 45 resiliently urge the frame means 39 towards an upright position, yieldingly resisting angular movement of the frame means 39.

The spring means 43 tend to urge the frame means 39 into the desired vertical position. A substantially vertical link means 52 is also pivotally connected with the lower portion of the frame means 39 and may pivotally connect with the pivot means 47.

A nut means 53 is threadedly connected with the link means 52. The spring means 43 is slidably positioned on link 52 and positioned between the nut means 53 and a sleeve 54. This sleeve 54 is rotatably mounted within hub 55. A plate 56 (Fig. 3) secures the sleeve 54 in place. The hub 55 is cut away, top and bottom, to permit the spring means 43, link 52 and nut means 57 to move in such cut away portions. Nut means 57 serves to tension spring 43 between nut means 53 and sleeve 54. The hub 55 is connected with bell crank lever 58 and may be integral therewith. Bell crank lever 58 is pivotally supported by a shaft 70 which is mounted on the main frame 10 of the machine. The other arm of the bell crank lever 58 connects with adjusting means to vertically position the sleeve 54. By vertically positioning the sleeve 54, the frame 39 and in turn the feed bed 19 are adjustably vertically positioned. The adjusting means for angularly moving the bell crank lever 58 may be in the form of a link 59 having one end pivotally connected with the bell crank lever 58 and the other

end connected with a screw 60. A worm wheel 62 is rotatably mounted within a frame means 61 attached to the main frame 10 of the machine. The worm wheel 62 is internally threadedly connected with the screw 60 and meshes with a worm 63. Thus by angularly moving the worm 63 through the worm wheel and links and levers shown, the frame means 39 may be vertically adjusted. Also similar spring tension will be provided by the spring means 43 regardless of the vertical position of the frame means 39.

In Fig. 6 of the drawings we have shown a modified form of the invention. Here a frame means 64 (similar to frame means 23) supports two upper feed rolls 65 and 66. The feed rolls 65 and 66 are connected to a source of power (not shown). The lower feed rolls 67 and 68 are mounted in a frame means 69 which is similarly mounted to the frame means 39. The parts of the supporting means for the frame means 69, being identical with the supporting means of the frame means 39, are similarly numbered and no further description thereof will be given.

Thus, we have provided means resiliently supporting a frame which is pivotally secured on a swinging portion of a pivotally mounted arm.

On such frame may be mounted a feed bed or feed rolls as desired. This provides a movement of a feed bed which may be likened to the movement of a person's arm and hand, viz., the arm may rise and fall at the shoulder joint and the hand may rise and fall at the wrist joint with or independent of the movement at the shoulder joint.

In the foregoing we have described the invention as applicable to a planing device, such as disclosed in our co-pending application Serial No. 91,568, Patent No. 2,102,186, dated Dec. 14, 1937. In such a planing device the lower bed is resiliently mounted as distinguished from the prior art planing machines where the upper beds are resiliently mounted. Obviously the invention herein can be readily adapted to ordinary planing machines, as well as to the planing mechanism disclosed in said application Serial No. 91,568.

Obviously, changes may be made in the forms, dimensions and arrangement of the parts of our invention, without departing from the principle thereof, the above setting forth only preferred forms of embodiment.

We claim:

1. In a device of the class described, a feeding member; a feeding member supporting frame means; an upper pivotally mounted supporting means having its swinging portion pivotally connected with said supporting frame means; and a lower resiliently mounted supporting means connected with said supporting frame means and resisting the movement in two directions of the feeding member supporting frame means afforded by the upper pivotally mounted supporting means.

2. In a device of the class described, a feeding member; a feeding member supporting frame means supporting said feeding member for feeding in substantially a horizontal plane; an up-

per pivotally mounted supporting means having its swinging portion pivotally connected with said supporting frame means; a substantially vertically positioned resiliently supported member pivotally connected with the lower portion of said supporting frame means; and a substantially horizontally positioned resiliently supported member pivotally connected with the lower portion of said supporting frame means, whereby movement of the frame means and feeding member supported thereby will be resiliently resisted in horizontal and vertical directions.

3. In a device of the class described, a feeding member; a feeding member supporting frame means supporting said feeding member for feeding in substantially a horizontal plane; an upper pivotally mounted supporting means having its swinging portion pivotally connected with said supporting frame means; a substantially vertically positioned resiliently and pivotally supported member having its swinging portion pivotally connected with the lower portion of said supporting frame means; and a substantially horizontally positioned resiliently and pivotally supported member having its swinging portion pivotally connected with the lower portion of said supporting frame means, whereby movement of the frame means and feeding member supported thereby will be resiliently resisted in horizontal and vertical directions.

4. In a device of the class described, a feeding member; a feeding member supporting frame means supporting said feeding member for feeding in substantially a horizontal plane; an upper pivotally mounted supporting means having its swinging portion pivotally connected with said supporting frame means; a substantially vertically positioned resiliently and pivotally supported member having its swinging portion pivotally connected with the lower portion of said supporting frame means; an adjusting means for moving said last mentioned member in a vertical direction; and a substantially horizontally positioned resiliently and pivotally supported member having its swinging portion pivotally connected with the lower portion of said supporting frame means, whereby movement of the frame means and feeding member supported thereby will be resiliently resisted in horizontal and vertical directions.

5. In a device of the class described, a feeding member comprising spaced apart feeding devices; a feeding member supporting frame means mounting said spaced apart feeding devices; a pivotally mounted supporting means having its swinging portion pivotally connected with said supporting frame means intermediate the spaced apart feeding devices, whereby the spaced apart feeding devices may angularly move as respects the pivotal mounting of the frame means and as respects the pivotal mounting of the supporting means; and a resiliently mounted supporting means connected with said supporting frame means and resisting said movements of the feeding devices.

FREDERICK A. NICHOLSON.
WILMOT T. PRITCHARD.
